UNITED STATES PATENT OFFICE.

BERNHARD KRÄMER, OF CHARLOTTENBURG, GERMANY, ASSIGNOR TO GENERAL ELECTRIC COMPANY, A CORPORATION OF NEW YORK.

FUEL-PUMP FOR INTERNAL-COMBUSTION ENGINES.

1,158,061.

Specification of Letters Patent.

Patented Oct. 26, 1915.

Application filed October 30, 1912. Serial No. 728,665.

To all whom it may concern:

Be it known that I, BERNHARD KRÄMER, a subject of the Emperor of Germany, residing at Charlottenburg, Germany, have 5 invented certain new and useful Improvements in Fuel-Pumps for Internal-Combustion Engines, of which the following is a specification.

The present invention relates to pumps 10 for supplying fuel, such as crude oil, to internal combustion engines and in particular to that type wherein air in the combustion space is compressed to a temperature sufficiently high to ignite the injected 15 fuel. Such an engine when operated at constant speed requires the fuel to be supplied thereto in exact proportion to the load.

The object of my invention is to provide 20 a fuel pump and governing mechanism therefor of improved and simple construction, and one which will be reliable in operation.

For a consideration of what I believe to 25 be novel and my invention, attention is directed to the accompanying specification and the claims appended thereto.

In the accompanying drawing which is 30 illustrative of my invention Figure 1 is a plan view of a multi-cylinder pump; Fig. 2 is a section taken on line A—A of Fig. 1, and Fig. 3 is a view in end elevation of an engine fitted with my fuel pump.

Referring to Fig. 3, 4 indicates a multi-cylinder internal combustion engine adapted 35 to be operated with crude oil as the fuel. 5 indicates the main shaft thereof, and 6 the pump shaft. This shaft may also be employed to actuate the cams for opening and closing the various fuel and other main 40 valves. The shafts 5 and 6 are connected together by a chain 7 or other suitable power transmitting means. As shown the shaft 6 revolves at half the speed of the main shaft. The speed relation between 45 these shafts will depend upon the type of engine, as is well understood. 8 indicates a pump casing which is provided with as many cylinders 9 as is desired. In each of 50 these cylinders is a plunger 10 which is raised by the spring 11. For each cylinder there is a spring seated discharge valve 12 that controls the passage of fuel through the pipe 13 leading to an engine cylinder. Each cylinder is also provided with a suc- 55 tion valve 14 of the piston type, said valve

being provided with a plurality of axially extending grooves 15 through which the fuel passes from the supply chamber 16 when the valve is open. The valve is opened by a spring 15^a working against the cam. The several plungers are actuated by the shaft 6, said shaft being provided with as many cams 17 as there are plungers. Each cam as it revolves is arranged to depress its plunger against the action of the spring 11 and discharge fuel through the spring seated valve 12 or back into the chamber 16 depending upon the amount of opening of the suction valve 14. The shaft 6 is supported by suitable bearings 18 and on one end thereof 60 is the gear 19 which meshes with a similar gear carried by the shaft 20. The speed relation of the shafts 6 and 20 is 1 to 1. Splined on the shaft 20 is a sleeve 21 which is adapted to be moved longitudinally thereon by the speed governor 22. Mounted on the sleeve are cams 23 which control the operation of the suction valves 14. These cams vary uniformly in radius from one end to the other in an axial direction so that as 65 the sleeve 21 which carries them is moved along the shaft, the relation of the cams to the suction valves and hence their effect thereon will be varied. From Fig. 2 it will be seen that the cams 17 and 23 occupy the 70 same angular position with respect to the shafts. From Fig. 1 it will be seen that the cams for actuating the right-hand pump and controlling its suction valve are displaced 75 from those on the left hand side by 90° 70 so that the right hand pump will deliver its charge of fuel before the left-hand one. This arrangement is useful in multi-cylinder engines whose cylinders fire one after the other and where it is desired to supply fuel 80 to each pulverizer as much in advance of the opening of its needle valve as possible. It is to be noted that the suction valve cams 23 are relatively wide at one end and taper to a point at the other. The object 85 of this arrangement is to permit of a variation in the period that the suction valve is open or closed.

The operation of my invention is as follows: Assuming that the engine has been 90 properly started, the shaft 6 turns the cam 17 and when the latter engages the roller on the upper end of the plunger the shaft depresses it on the discharge stroke and subsequently the spring 11 raises the plunger to 100 105 110

the position shown. While this action is taking place the cam 23 has been depressing the suction valve 14 to a greater or less extent, and at some time in its stroke it closes 5 and thereafter fuel flows through the discharge valve. With the parts in the position shown in Fig. 2 all of the fuel displaced by the plunger 10 would flow back to the chamber 16 because it could freely pass through 10 the grooves 15 in the suction valve. On the other hand, if the cam 23 had been moved to the left (see Fig. 1) said cam would have depressed and closed the suction valve for 15 a longer or shorter period of time depending on its position, and during the time that the suction valve was closed fuel would be discharged through the discharge valve 12 to the engine.

My improved pump has the advantage of 20 being extremely simple in construction and reliable in operation. The parts are very accessible and it is an easy matter to take it down for the purpose of inspection or repair.

25 The arrangement is particularly advantageous for a multicylinder pump such as are commonly used for oil engines because all of the plungers can be arranged in one row and all of the suction valves in another row 30 with a means common thereto for actuating.

In accordance with the provisions of the patent statutes, I have described the principle of operation of my invention together with the apparatus which I now consider to 35 represent the best embodiment thereof; but I desire to have it understood that the apparatus shown is only illustrative, and that the invention can be carried out by other means.

40 What I claim as new and desire to secure by Letters Patent of the United States, is:—

1. In a pump, the combination of a cylinder, a plunger therefor, suction and discharge valves for the cylinder, a pair of 45 shafts, gearing between the shafts, a cam on one shaft for actuating the plunger, a cam on the second shaft for controlling the suc-

tion valve, said last named cam having an inclined face and being axially movable on the shaft to vary the periods of opening and 50 closing of the suction valve, and a governor for moving such cam.

2. In a pump, the combination of a cylinder, a plunger therefor, suction and discharge valves for the cylinder, a pair of 55 shafts, gearing between the shafts causing them to revolve at the same speed, a cam on one shaft for actuating the plunger, a cam on the second shaft for controlling the suction valve, said cams occupying the same 60 angular position on their respective shafts and said last named cam having an inclined face and being movable axially on the shaft, and a speed governor mounted on the shaft which carries the axially movable cam for 65 moving it longitudinally thereon.

3. In a pump, the combination of a cylinder, a plunger therefor, suction and discharge valves for the cylinder, a shaft for actuating the plunger, a second shaft geared 70 to the first, a cam carrying sleeve on the second shaft, and a governor driven by one of the shafts for moving the cam sleeve longitudinally to vary the action of the suction valve.

4. In a pump, the combination of cylinders arranged in a row in the same plane, plungers therefor, suction valves arranged in a second and parallel plane, parallel cam shafts, means on one of said shafts for actuating the plungers, a member movable axially of the other shaft, cams carried by said member for actuating the suction valves, the action of said cams on the suction valves being varied according to their axial position thereon, a governor for moving said member axially on its shaft, and means for operating the shafts.

In witness whereof, I have hereunto set my hand.

BERNHARD KRÄMER.
